DUPLICATING MACHINE

Frank Ronald Ford, Sparkbrook, Birmingham,
EnglandApplication July 25, 1942, Serial No. 452,276
In Great Britain May 20, 1941

9 Claims.

(Cl. 91—38)

This invention relates to duplicating machines of the kind wherein a master sheet having the matter to be reproduced in reverse is mounted on a cylinder with which co-operates a pressure roller, and wherein the copy sheets are fed between the master on the cylinder and the pressure roller and are moistened by means of a moistening pad before being brought into contact with the master sheet.

One of the objects of the present invention is to provide for more uniform moistening of the copy sheet over the length of the sheet.

Machines of the kind referred to are known wherein the moistening device is movable and has an automatic oscillating motion. In such machines there is an impact effect when the moistening device is brought into contact with the copy sheet, and due to the momentum of the moving parts, there is a tendency to impart too much moisture to the leading part of the copy sheet.

Machines of the kind referred to are also known wherein the moistening device is stationary and wherein the copy sheet is lightly pressed on to the surface of the stationary moistener before passing to the cylinder. In such machines, however, the copy sheet is moistened on the underside and it has therefore been necessary hitherto to make such machines with the pressure roller above the cylinder, the actual reproduction on the copy sheet taking place on the underside thereof, and therefore not being visible to the operator.

Further, in such machines, unless said means are provided, the copy sheets are delivered face downwards.

A further object of the present invention is to provide a machine which will have the advantages of a stationary moistener, and wherein the copy sheets will be moistened on the upper side and reproduction will take place on the upper side of the copy sheets, and the copy sheets will be delivered from the machine without any special provisions face upwards.

A further object of the present invention is to provide for more uniform moistening across the width of the copy sheet.

In duplicating machines of the kind referred to, moistening devices are known wherein the liquid is conveyed to an elongated moistening pad by means of a wick extending along the length of the pad and in contact with one side thereof, the ends of the wick extending into the moistening liquid in a tank. With this arrangement there is a strong tendency for the centre part of the

moistening pad to be starved of liquid, and the end parts thereof to receive too much moistening liquid.

The present invention seeks to provide means to cure this defect.

Further, in machines of the kind to which this invention relates, during working a part of the surface of the moistening pad is necessarily exposed, and when working is interrupted, if this surface is left exposed, evaporation of the moistening liquid takes place at such surface rapidly so that the moistening liquid, which is volatile, is wasted to a serious extent.

Referring to the drawings:

15. Figure 1 is a sectional view in end elevation showing one form of construction in accordance with this invention.

Figure 2 is a plan view.

20. Figure 3 is a sectional view in end elevation showing a modified form of the invention.

Figure 4 is a plan view of the construction shown in Fig. 3.

25. Figure 5 is a sectional view in end elevation upon an enlarged scale showing the moistener and the feed table used in the construction shown in Figs. 4 and 5 in the working position.

Figure 6 is a view similar to Figure 3 but showing the feed table in the position in which it covers the normally exposed part of the moistening pad.

Figure 7 is a perspective view showing the separate parts of the moistener used in the construction shown in Figs. 3 to 6.

30. Figure 8 is a perspective view showing a further modification.

Figure 9 is a sectional view of the construction shown in Figure 8.

35. In the construction illustrated in Figures 1 and 2, the machine comprises two side plates 10 placed vertically in spaced relationship and held together by horizontally extending tie rods 11.

The cylinder 12 is provided with a spindle 13 which is supported in bearings carried by the side plates, the cylinder being placed horizontally and extending between the upper parts of the side plates. Fixed in a determined position at one end or at both ends of the cylinder is a separate portion 14 of considerably reduced diameter in which there is a notch 15, and a spring actuated plunger 16 engages this notch once during every revolution of the cylinder so as to check the rotation thereof at a definite position which is the feed-in position for the copy sheets.

40. The cylinder 12 is further provided with

means, such as a hinged or radially sliding plate or member, arranged longitudinally on its circumference for gripping the leading edge of the master sheet.

In addition the cylinder at one or both ends is provided with a cam 17. Preferably two of these cams are provided and they co-operate with levers 18 pivoted to the inner sides of the side plates at 19, which levers carry the bar or roller 20 employed to press the copy sheets against the underside of the moistening member 21. The arrangement is preferably such that the levers are urged by springs 22, one to each lever, the pressure of which is adjustable, towards the moistening member, and the cams 17 on the cylinder operate, at the feed-in position, to move the levers 18 downwardly so as to withdraw the bar or roller 20 from the moistening member and to leave a gap through which the leading ends of the copy sheets can be fed into the bite of the cylinder 12 and pressure roller 23.

The pressure roller 23 is arranged on a horizontal axis and is preferably of smaller diameter than the cylinder. It is arranged below the cylinder although not necessarily directly below the axis thereof. The pressure roller may be, as shown, placed somewhat nearer the feed-in side of the machine than is the axis of the cylinder.

The pressure roller 23 is provided with a spindle or with trunnions 24 at its ends which are mounted in bearing blocks mounted for vertical sliding movement in guides provided on the side plates of the frame, and the bearing blocks are supported by means of springs, the pressure of which is adjustable.

The moistening member is in the form of a liquid container 25 provided with one or more wicks 26 extending upwardly from the liquid, thereby taking liquid from the container by capillary action and over the edge of a dividing plate 27, and then downwardly to an absorbent moistening pad 21. The container 25 is provided with two laterally extending flanges at its ends which slide into slots, one of which can be seen at 39, these slots being provided in the inner surfaces of the side plates. The container is locked in position by a locking screw 40 extending through one of the side plates and bearing on the edge of one of the lateral projections of the container. As will be seen from Figure 1, on the left-hand side of the dividing plate 27 is the container for liquid, while the space between the dividing plate 27 and the right-hand side of the container forms a chamber for the part of the wick extending from the container to the moistening pad.

Immediately above the wicks and the edge of the dividing plate 27 is placed a bar 28 which is movable vertically by means of thumb screws 29 on the outside of the container top 30. When these screws 29 are tightened, the bar 28 compresses the wicks against the edge of the dividing plate, thereby acting as a fluid control. The moistening pad 21 may be constructed in the well known manner and is mounted in a sheet metal container 31 engaging its upper and lower sides and its edges, but leaving a portion of its lower side exposed. This exposed portion of the moistening pad is disposed as near to the line of contact between the cylinder 12 and the pressure roller 23 as possible, and of course the bar 28 (or roller) which is employed to press the copy sheets upwardly on to the exposed part of the moistening pad, is situated directly below the exposed part of the moistening pad.

The levers which carry the bar or roller 20 for pressing the copy sheets against the pad are provided with rollers 32 which are acted upon by the cams 17 associated with the cylinder, the cams moving the levers so as to bring the bar or roller 20 for pressing the copy sheets, away from the moistening pad at the feed-in position. Each of these levers 18 is provided with a plate 33 which is slotted, and through this slot extends a vertically disposed pin 34 which is mounted in a stud 9 secured to the side plate. Each of these pins is provided with an adjustable abutment 35 between which and the underside of the lever operates a spring 22. The pressure of these springs is individually adjustable.

The levers 18 are provided with upwardly extending brackets 37 carrying at their ends the ends of the spindle on which the roller is mounted, or carrying the ends of the bar 20.

The feed table 38 is arranged horizontally or in an inclined position, and in either case a portion 36 situated at its delivery edge is inclined upwardly so as to deflect the copy sheets onto the exposed portion of the underside of the moistening pad.

In Figures 3 to 9 of the drawings, the invention is shown applied to a machine wherein the pressure roller 23 is situated below the cylinder 12 upon which the master sheet is clamped by any suitable form of clamp operated by a lever 112 pivoted at 113 on the end of the cylinder.

The spindle 13 of the cylinder is supported in spaced side plates 10 which are held in spaced and parallel relationship by tie bolts 11.

As is known in this type of machine a check device is provided for checking the rotation of the cylinder at a particular position during each rotation. This check device comprises a roller 16 carried in a fork 190 attached to an arm 120 pivoted at 191 to the side plate 10. The fork 190 has a shank 118 engaging a support 11 on the side plate 10 and acted upon by a spring 119 which operates between a nut 193 and a collar 194 through which the shank 118 can slide. This roller enters a notch 15 in a flange 14 formed or attached to the cylinder.

The pressure roller 23 has a spindle 24 mounted in bearings in the known way, and this pressure roller is pressed towards the cylinder by means of springs 124 which operate upon the said bearing blocks. The pressure of the springs 124 may be adjustable, and the pressure roller 23 may be moved away from the cylinder by levers 125.

In this machine the copy papers are passed between the cylinder and the pressure roller, and it is necessary to moisten their upper sides before they do so. For this purpose a moistener 126 is provided, the copy sheets being fed to the moistener over a feed table 38. As the copy sheets leave the feed table, they are pressed against the underside of the moistening pad 151 by means of a pressure bar or roller 20. This pressure bar or roller is carried by a pair of levers 18 pivoted at 19 to the frame, the levers 18 being provided with extensions 33 which are acted upon by springs 22 mounted upon pins 34 carried by studs 9 attached to the side plates 10.

The springs 22 press the levers 18 upwardly so that the pressure bar or roller 20 presses the copy sheets into contact with the underside of the moistening pad 21.

The levers 18, however, are, once each revolution of the cylinder, swung downwardly by means of cams, one of which can be seen at 17 on the end of the cylinder, these cams operating on rolls

ers 32 connected by arms 138 to the levers 18. When the cams are in their operative positions, the pressure bar or roller 20 is moved away from the moistener 151 so as to provide an opening through which the copy sheet can be fed to the line of contact between the pressure roller 23 and the cylinder 12. It is in this position that the check device 16 checks the motion of the cylinder. After the cams 17 have left the rollers 32, the levers 18 swing upwardly so that the bar or roller 20 applies pressure to the copy sheet.

The moistener 126 is shown in detail in Figures 5, 6 and 7, and comprises a tank 139 having a filler opening closed by a cap 140. At two of these corners and at the upper side the tank is provided with openings 141. Secured to the upper surface of the tank at each end are tubes 142 each having a horizontal portion and an inclined portion 143.

Mounted on the upper ends of the inclined portions 143 is a carrier plate 144. This carrier plate is provided with flanges 145 at opposite ends which slide into slots 146 on the inner sides of the frame members 10 until they engage stops 147.

On the underside the carrier plate is provided with shoulders 148 near its ends and on its upper side it is provided with a rectangular recess 149, in the bottom of which is a slot 150 which extends through its thickness.

The moistening pad is shown at 151 and has opposite edges covered with doe skin or the like 152, the arrangement being such that the pad provides four working surfaces, one at each of the opposite sides of each edge. When one working surface is worn or otherwise ineffective, the pad can be turned over to bring the opposite side into operation, and when this second surface has become ineffective, the pad can be reversed to bring the opposite edge into the working position, and this edge also provides two working surfaces.

The pad 151 is mounted in a tray plate 153, this tray plate having a part 154 of channel section which engages over the edge of a carrier plate 144.

At its ends the tray plate is provided with flanges 155 which locate the moistening pad against endwise movement. Further, the tray plate is provided with four plate springs 156 which hold the pad down firmly on to the tray portion of the plate.

These springs 156 bear upon pieces of wire gauze 157 resting on the top of the moistening pad proper, and it will be observed that the ends of the pieces of gauze 157 are spaced apart so that there is a gap 158 between them.

The flange 159 of the channel section part of the tray plate is provided with downward depressions 160 formed by pressing the plate, and at the centre of its length the flange is notched as shown at 161.

The main wick 162 has the centre part of its length disposed in the slot 150 of the plate 144 with the ends of the wick extending down through the inclined parts 143 of the tubes 142 and thence into the tank 139.

Two shield plates 163 are placed over the wick 162 near its ends, these shield plates being placed in the recess 149 and resting on the shoulders at the bottom of the recess. There is a space between these two shield plates 163 as seen clearly in Figure 7.

Above the shield plates is placed the auxiliary wick 164. This wick may extend to the ends of the recess 149, or if preferred, its ends may be

taken down through the tubes 142, 143 into the tank 139.

Above the auxiliary wick 164 is a top plate 165 having a flange 166, this plate being attached to the carrier plate 144 by the screws 167.

When this plate is in position, the tray plate 153 carrying the moistening pad proper is slid into position by pushing it forwardly, this plate sliding between the shoulders 148. The tray plate is provided with handles 168 to facilitate removal.

When the tray plate has been pushed home, the projections 160 engage in depressions 182 provided in the top plate 165.

In each of the parts 142 is provided a stationary block 169 and a moving block 170. Through each block 169 is a screw 171 operable by a head 172. The screw may have two threads, one at 173 and the other at 174, engaging with the moving block 170, and these threads may be of opposite hand so that when the screw is turned, the block 170 is advanced or moved backwardly. The block 170 can be advanced to exert pressure upon the end portions of the main wick 162 so as to regulate the flow of liquid therethrough. If the auxiliary wick 164 also has its ends extending down through the tubular parts 143, they also may be acted upon by the blocks 170.

In operation the liquid is fed by capillary action up through the main wick and thence to the moistening pad, but the flow of liquid to the end portions of the moistening pad may be somewhat modified by the presence of the pieces of wire gauze 157.

If the ends of the auxiliary wick 164 are taken to the tank, further liquid is brought upwardly in this way and fed to the centre part only of the main wick. If, however, the auxiliary wick is, as shown in Figure 7, of a length equal to the length of the slot in the carrier plate, it acts as a distributor tending to convey the moisture from the end portions of the main wick between the ends of the shield plates 163 and the ends of the recesses in the carrier plate 144 to the centre part of the main wick which tends to be starved of moisture.

During working, the underside of the forward edge of the moistening pad is necessarily exposed so that the copy sheets may make contact therewith, and it is a feature of the present invention to provide means for covering this exposed surface when the machine is not in use.

One method of doing this is shown in Figures 8 and 9, wherein the tray plate 153 is modified by making it slightly deeper, and slidably mounted therein is a cover plate 175, this cover plate being provided with handle portions 176 which are associated with parts 177 which slide through slots in the tray plate. The cover plate 175 slides under the moistening pad and between the moistening pad and the tray plate. The cover plate 175 can be drawn back by pulling on the handle 176 to expose the underside of the forward part of the moistening pad.

An alternative method of providing for covering the exposed part of the moistening pad is shown in Figures 5 and 6, wherein the feed table 38 is pivoted at 182 to a pair of angle section plates 178. The horizontal flanges of these angles slide in the slots 146 in the side frames of the machine. The feed table 38 is provided with lateral extensions 179 at opposite edges which also engage in the slots 146 so that when in this normal position as shown in Figure 5, the feed table cannot rock about the pivots 182. The feed

table, however, can be pushed forwardly until the lateral projections 179 come into contact with slots 180 in the side frames, permitting the feed table to rock into the position shown in Figure 6.

The angle section plates to which the feed table is pivoted can be locked in the slots in the side plates by means of a screw 181.

What I claim then is:

1. A moistening device for a duplicating machine of the kind described, comprising a tank for containing the moistening liquid, a support for a moistening pad, a moistening pad in said support, said moistening pad being of elongated strip-like form, a main wick extending along the pad and in contact with one side thereof, the said main wick having its end portions disposed in the liquid in the tank, an auxiliary wick extending along that part of the main wick which is in contact with the pad, said auxiliary wick and said pad contacting the main wick at opposite sides, and shield plates disposed between the main and auxiliary wicks, said shield plates being spaced apart along the length of the auxiliary wick so as to allow the auxiliary wick to contact the main wick at the centre and at the parts which contact the ends of the pad.

2. A moistening device according to claim 1, having strips of perforated material interposed between the end portions of the pad and the adjacent surface of the main wick.

3. A moistening device according to claim 1, wherein the support for the moistening pad comprises a pair of spaced tubes secured to the tank and extending upwardly therefrom, a carrier plate, having an elongated slot, mounted on the upper ends of the tubes, said tubes communicating with the tank and with the slot in the carrier plate, a tray plate for holding the pad, and means for detachably mounting the tray plate on the carrier plate.

4. A moistening device according to claim 1, wherein the support for the moistening pad comprises a pair of spaced tubes secured to the tank and extending upwardly therefrom, a carrier plate, having an elongated slot, mounted on the upper ends of the tubes, said carrier plate being recessed at the top, the width of the recess being greater than the width of the slot, a tray plate for holding the pad, said tray plate having one edge of channel form for pushing over one edge of the carrier plate, plate springs on said tray plate extending over the moistening pad when in position on the plate, and means on the tray plate for locating the moistening pad against endwise movement.

5. A moistening device according to claim 1, wherein the support for the moistening pad comprises a pair of spaced tubes secured to the tank and extending upwardly therefrom, a carrier plate, having an elongated slot, mounted on the upper ends of the tubes, said carrier plate being recessed at the top, the width of the recess being greater than the width of the slot, and a tray plate for holding the pad, said tray plate having one edge of channel form for pushing over one

edge of the carrier plate, said tray plate and said carrier plate having registering projections and recesses for locating the tray plate on the carrier plate.

6. A moistening device according to claim 1, wherein the support for the moistening pad comprises a pair of spaced tubes secured to the tank and extending upwardly therefrom, a carrier plate, having an elongated slot, mounted on the upper ends of the tubes, said tubes communicating with the tank and with the slot in the carrier plate, a tray plate for holding the pad, a cover plate slidably mounted on said tray plate for covering the moistening pad when the machine is out of use, and means for detachably mounting the tray plate on the carrier plate.

7. A moistening device according to claim 1, wherein the support for the moistening pad comprises a pair of spaced tubes secured to the tank and extending upwardly therefrom, a carrier plate, having an elongated slot, mounted on the upper ends of the tubes, said tubes communicating with the tank and with the slot in the carrier plate, said tubes having lower portions extending across the top of the tank and upper portions disposed at an angle to the lower portions and extending upwardly, sliding blocks in said lower portions, means for advancing these blocks so as to press the wick against the walls of the tubes to regulate the flow of liquid, a tray plate for holding the pad, and means for detachably mounting the tray plate on the carrier plate.

8. A moistening device for a duplicating machine of the kind described, comprising a tank for containing the moistening liquid, a moistening pad, a support for the moistening pad engaging its upper and lower sides and its edges but leaving a portion of its lower side exposed, and a wick having one end disposed in the liquid in the tank, and the other end disposed in the said support and in contact with one side of said pad, said wick conveying the liquid to said pad.

9. A moistening device for a duplicating machine of the kind described, comprising a tank for containing the moistening liquid, a moistening pad, a support for the moistening pad engaging its upper and lower sides and its edges but leaving a portion of its lower side exposed, said support comprising an upper plate forming the bottom of the tank and having a dividing plate extending upwardly within the tank to a position near the top of the tank, said dividing plate dividing the tank into a liquid containing chamber and a wick housing, said upper plate having an opening extending through its thickness, and a recess in its lower side for accommodating one end of the wick, said opening placing said wick housing in communication with said recess, and a wick having one end disposed in the liquid in the tank, said wick being looped over the top edge of said dividing plate and having its other end projecting through said opening and into said recess to contact said pad.

FRANK RONALD FORD.
